UNITED STATES PATENT OFFICE.

SAMUEL J. HURWITZ, OF YOUNGSTOWN, OHIO.

VULCANIZER.

1,357,984.

Specification of Letters Patent. Patented Nov. 9, 1920.

Application filed December 29, 1919. Serial No. 348,144.

To all whom it may concern:

Be it known that I, SAMUEL J. HURWITZ, a citizen of Russia, residing at Youngstown, in the county of Mahoning and State of 5 Ohio, have invented new and useful Improvements in Vulcanizers, of which the following is a specification.

The object of my present invention is the provision of a compact, easily manipulated 10 and highly efficient electrical device, designed more particularly, though not necessarily, for vulcanizing the inner tubes and casings of pneumatic tires.

To the attainment of the foregoing, the 15 invention consists in the improvement as hereinafter described and definitely claimed.

In the accompanying drawings, hereby made a part hereof:

Figure 1 is a plan view of the device constituting the best practical embodiment of 20 my invention of which I am cognizant.

Fig. 2 is a side elevation of the same.

Fig. 3 is an inverted plan.

Figs. 4 to 9 are detail views bringing out 25 certain features of the construction herein-after explicitly alluded to.

Similar numerals of reference designate corresponding parts in all of the views of the drawings.

I prefer to have my vulcanizer comprise 30 two members 1 and 2, and I also prefer to cast each of the said members of metal, or of some suitable alloy. Included in the member 1 is a central hollow body portion

35 3, best shown in Figs. 1, 2, 4 and 6, and arms 4, integral with and reaching in opposite directions from the body 3; one of the said arms 4 being provided adjacent to its outer end with an aperture; and the

40 other arm 4 having in its outer end a bifurcation 5. The hollow body 3 of the member 1 is open at one side, as appears in Figs. 4 and 5. The member 2 is best shown in Figs. 3, 7, 8 and 9, and by comparison of

45 said figures, it will be understood as including an annular body portion 6 and arms 7 reaching in opposite directions from the body 6 and integral therewith. At their outer ends the arms 7 are bifurcated, as indicated by 8, and provided with transverse apertures 9, and by reference to Figs. 2 and 3, it will be understood that pivoted in the bifurcated portions 8 are the terminals 10

50 of longitudinally swinging threaded bolts 11 on which are stops 12 adapted to bring up against the member 1, with a view to

limiting the inward movements of the members 1 and 2 relatively to each other. The bolts 11 are removably arranged in the bifurcations, respectively, of the arms 4, and are equipped with wing-nuts 13 to provide the necessary pressure. The said wing-nuts 13 are readily removable, and the member 1 is susceptible of being reversed on the bolts 11. It will also be apparent that while 60 designed more particularly for use in association, each of the members 1 and 2 is adapted to be used to advantage independently of the other.

By comparison of Figs. 4, 5 and 6, the 70 hollow body 3 of the member 1 will be understood as containing the following elements, viz: an insulating layer 14, preferably of mica, insulating layers 14^a at right angles to the layer 14, Figs. 5 and 6, an insulating body 15, preferably of some appropriate plastic insulating material, conductive strips 16, conductive plates 17 and 18, and a resistance coil 19. The layer 14 is superimposed upon the bottom of the body 80 3, and immediately above the said layer 14 are the conductive strips 16, the inner portions of which are bent upon themselves to afford strong bearings for connecting screws 20, and the outer ends of which are angularly disposed, as indicated by 21, and are opposed to the layers 14^a for the passage of connecting screws 22, which also extend through insulating bushings 23, and are designed to be electrically connected with the 85 opposite poles of the source of electrical energy. The body 15 is provided with a central pocket 24, and disposed snugly in said pocket is the depressed portion of the conductive plate 17 which is preferably of copper; the screws 20 being carried through comparatively large apertures in the plate 17 and also through one or more insulating layers 25, and serving for the connection of the terminals of the resistance coil 19. The 90 plate 18 is also preferably of copper, and is provided, by preference, with a curvilinear central portion designed to lend itself to the curvature of the tube or casing to be acted on. As best shown in Fig. 4, the conductive plates 17 and 18 are connected together and to the body 3 by screws 26, so that when the said screws are removed, access may be readily gained to the resistance coil 19 and the chamber in which the same is disposed. 100 At this point I would have it understood 105 that it is within the purview of my inven-

tion to fill the chamber containing the resistance coil with oil, with a view to contributing to the adequate heating of the plate 18, though I have deemed it unnecessary to illustrate the said oil.

Bridging the annular body 6 of the member 2, as best shown in Figs. 3 and 8, is a diametrical bar 30 that is connected to said body 6 through the medium of screws 31, and pivotally connected at 32 to the said bar 30 is the rockable member of my improvement, so denominated because of its capacity to rock and thereby accommodate itself to the particular surface to which it is opposed. The said rockable member, numbered 33, is hollow, and is equipped in a generally similar manner to the body 3 of the member 1—*i. e.*, contains an insulating strip 34, of mica or other insulating material, a body 35 of insulating material, conductive strips 36, conductive plates 37 and 38, preferably of copper, and a resistance coil 39, the said resistance coil being arranged in a chamber formed between the plates 37 and 38, and being connected by screws 39^x with the conductive strips 36, which are connected, in turn, to screws 40, adapted for electrical connection with the opposite poles of a source of electrical energy. Manifestly when desired the chamber containing the resistance coil 39 may be filled with oil or equivalent substance for the purpose hereinbefore referred to with reference to the chamber containing the resistance coil 19. As appears in Figs. 8 and 9, one or more strips of insulating material is interposed between the plate 37 at the bottom of the chamber and the resistance coil 39.

It will be apparent from the foregoing that my novel vulcanizing device is susceptible of ready manipulation in practice, and the member 1 may be arranged with its plate 18 opposed to the plate 38 of the rockable member 33; or said member 1 may be reversed and arranged with its flat side 40 opposite to the plate 38 of the rockable member, according to the character of the vulcanizing to be accomplished. It will further be apparent that my novel vulcanizer is exceedingly strong and durable, and that when it is desired to put the same into use, it is simply necessary as a condition precedent to electrically connect the resistance coils with the poles of a source of electrical energy.

As before indicated, the members of my novel device are, when occasion demands, adapted to be disassociated, and each used independently of the other.

Having described my invention, what I claim and desire to secure by Letters-Patent, is:

1. The combination in a vulcanizer, of a hollow body, a body of insulating material

arranged in said hollow body and having a depression, conductive strips interposed between said bodies, insulating means interposed between the conductive strips and the first-named body, inner and outer heat conductive plates opposed to the said bodies, and the inner conductive plate conforming to said depression whereby a chamber is formed between the plates, a resistance coil disposed in said chamber and electrically connected with said conductive strips, and means connected to the conductive strips and extending exteriorly of the body for electrical connection with a source of electrical energy.

2. The combination in a vulcanizer, of a body containing a chamber the exposed wall of which is of heat conductive material, a resistance coil in said chamber, and means connected with the resistance coil and extending to the exterior of the body for the connection of the resistance coil with the opposite poles of a source of electrical energy, the said chamber being charged with substance adapted to conduct to the heating of the said exposed wall.

3. In a vulcanizer, the combination of a hollow body, a body of insulating material arranged therein and having a depression, conductive strips interposed between the bottom of the first-named body and the second-named body, insulating material arranged to isolate said conductive strips from the first-named body, means connected to the conductive strips and extending outside the body for the connection of said strips to the opposite poles of a source of electrical energy, inner and outer heat conductive plates, the inner plate conforming to said depression whereby a chamber is formed between the plates, a resistance coil in the chamber, and means electrically connecting said resistance coil and the conductive strips.

4. In a vulcanizer, the combination of a hollow body, a body of insulating material arranged therein and having a depression, conductive strips interposed between the bottom of the first-named body and the second-named body, insulating material arranged to isolate said conductive strips from the first-named body, means connected to the conductive strips and extending outside the body for the connection of said strips to the opposite poles of a source of electrical energy, inner and outer heat conductive plates, the inner plate conforming to said depression whereby a chamber is formed between the plates, a resistance coil in the chamber, and screws connecting the resistance coil and the conductive strips; the said strips being bent upon themselves to afford increased thicknesses to receive and engage said screws.

5. A vulcanizer comprising opposed members, one of said members having a hollow

body and the other member carrying a rockable member including a hollow body, and each of the said hollow bodies having a chamber and a heat conductive plate forming one wall of the chamber, resistance coils arranged in said chambers and insulated from said bodies, means connected to the resistance coils and extending outside the

bodies for the electrical connection of the resistance coils with a source of electrical energy, and means adjustably and detachably connecting the two first-named members together.

In testimony whereof I affix my signature.

SAMUEL J. HURWITZ.
